UNITED STATES PATENT OFFICE.

MARY McABOY, OF MISSOULA, MONTANA.

DESIGN FOR A DOLL OR TOY FIGURE.

45,264.

Specification for Design.

Patented Feb. 17, 1914.

Application filed November 29, 1913. Serial No. 803,850. Term of patent 7 years.

To all whom it may concern:

Be it known that I, MARY McABOY, citizen of the United States, residing at Missoula, in the county of Missoula and State of Montana, have invented a certain new, original, and ornamental Design for a Doll or Toy Figure, of which the following is a specification, reference being had therein to the accompanying drawing, in which—

2 is a rear elevation of the doll or toy figure showing my new design.

I claim:

The ornamental design for a doll or toy figure as shown.

In testimony whereof I hereunto affix my signature in presence of two witnesses.

MARY McABOY.

Witnesses:

JAS. M. CONLON,
CHAS. F. HAYDEN.
